UNITED STATES PATENT OFFICE.

FRANCIS C. COPELAND, OF SAN FRANCISCO, CALIFORNIA.

DESIGN FOR A SMOKER'S SET.

Application filed August 27, 1927. Serial No. 23,223. Term of patent 7 years.

To all whom it may concern:

Be it known that I, FRANCIS C. COPELAND, a citizen of the United States, residing at the city and county of San Francisco, State of California, have invented a new, original, and ornamental Design for a Smoker's Set, of which the following is a specification, reference being had to the accompanying drawing, forming part thereof.

The figure is a perspective view of the article showing my design.

I claim:

The ornamental design for a smoker's set, substantially as shown.

FRANCIS C. COPELAND
